(57) **CLAIM**

The ornamental design for a license plate frame with connected tags, as shown and described.

DESCRIPTION

FIG. 1 is a perspective view of a license plate frame with connected tags.

FIG. 2 is a front side view of the claimed ornamental design.

FIG. 3 is a back side view of the claimed ornamental design.

FIG. 4 is a top view of the claimed ornamental design.

FIG. 5 is a bottom view of the claimed ornamental design.

FIG. 6 is a left side view of the claimed ornamental design; and,

FIG. 7 is a right side view of the claimed ornamental design.

The broken lines in the drawings illustrates the environment of the license plate frame with connected tags, which forms no part of the claimed design.
